(57) **CLAIM**

The ornamental design for a storage box, as shown and described.

DESCRIPTION

FIG. 1 is a rear, right and top perspective view of a storage box, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof, shown in a used condition; and,

FIG. 10 is a perspective view thereof, shown in a disassembled condition.

The broken lines shown in the drawings illustrate portions of the storage box that form no part of the claimed design.

1 Claim, 10 Drawing Sheets
